UNITED STATES PATENT OFFICE.

JAMES STANLEY AND THEODORE F. LEMASSENA, OF NEWARK, NEW JERSEY,
ASSIGNORS, BY MESNE ASSIGNMENTS, TO LILLIAN LEMASSENA, OF SAME
PLACE.

MANUFACTURE OF PORTIONS OF A HARNESS.

SPECIFICATION forming part of Letters Patent No. 293,535, dated February 12, 1884.

Application filed July 20, 1883. (No model.)

To all whom it may concern:

Be it known that we, JAS. STANLEY and T. F. LEMASSENA, citizens of the United States, residing in Newark, Essex county, New Jersey, have invented certain new and useful Improvements in Harness Manufacture, fully described and represented in the following specification and the accompanying drawings, forming a part of the same.

- 10 This invention relates to the formation of certain parts of harness and other analogous articles of a composition of scrap-leather protected from moisture by coating with a layer or covering of water-proof material.
- 15 The invention is applicable to all those parts of the harness—as collars, cruppers, saddles, trees, blinds, rosettes, trotting-balls, &c.—which do not require a combination of great flexibility and strength, and is shown in the 20 drawings annexed as applied to a horse-collar with certain modifications.

The method of manufacture will be described in reference to the collar shown, but would be precisely similar in connection with any other 25 part of the harness.

The process of manufacture we employ produces a perfectly solid and firm texture in the various articles of harness, and their durability is secured by baking or otherwise drying 30 a water-proof composition upon the surface of the article in such a manner as to form a seamless unbroken coating over its entire surface. The baking operation and the heat employed therein also tend to saturate the fibrous texture 35 of the article with water-proof material, so as to secure the utmost permanence in the effects of the coating applied to the surface of the article to protect it from moisture.

The process of manufacture is as follows: A 40 suitable mold, formed in several detachable parts, (so as to release the finished article,) is provided, and any kind of leather scraps are pasted together therein with an admixture of any suitable cement until the article is formed 45 of the desired shape.

In the case of all rounded articles—as for instance, the collar shown in the drawings—it is necessary to compress the article thus shaped

in a second or finishing mold to give it the smoothness and final form desired. The article may be partially dried before it is subjected to such finishing-mold, and is then better fitted to take a smooth surface and to retain the acquired form.

In the case of flat or rectangular articles it 55 is obvious that the pasting or shaping mold may be used as the pressing or finishing mold; but in such case the mold performs two distinct functions, and the pasting and final pressing are equally distinct operations. For the 60 pasting-mold we use plaster-of-paris, but prefer metal for the final mold, although the plaster mold is sometimes used. When fully pressed, the article is dried, either in or out of the mold, and when freed from volatile fluids 65 its surface is coated with a water-proof composition capable of protecting the substance from atmospheric influences. Japan or india-rubber varnish is most suitable for the purpose, and when such agents are used the article is preferably baked in an oven at such temperature as is required to harden the japan or vulcanize the india-rubber, and when the surface is thus coated with an unbroken shell of water-proof material the article is adapted to 70 endure great exposure to weather with very little and slow deterioration.

In the preparations of fabric or artificial leather compounded from leather scraps heretofore, the cement employed has usually been 80 of such a nature—as paste or glue—that moisture would readily penetrate the edges or surface of the fabric and disintegrate the same by destroying the adhesive power of the cement; but our invention obviates this defect, 85 which exists in artificial leather or compounds of scraps, by molding the article directly of the required form, without any joints, in one single piece, and by coating the entire surface of each required piece with a water-proof material, which is preferably baked upon and into the article.

In the drawings annexed, Figure 1 is a transverse section, and Fig. 2 is a rear view, of a horse-collar constructed as last described. 95 The section is taken on line *xx* in Fig. 2.

A is the collar, and B (in Fig. 2) indicates the scraps of leather which form the body of the article, the same being compressed into close contact with each other, especially upon 5 the outer parts of the substance, where it comes into contact with the shaping agents and receives the pressure. By such molding and pressure the entire article is consolidated into substantially a single piece, and possesses a 10 degree of strength not belonging to its separate fragments at all.

It will be seen from the above that our invention differs from other articles formed by pasting or securing leather scraps together, in 15 that no part of the article desired is sewed or cut or joined to another part by penetrating the surface, and that each article is constructed with an unbroken coat of water-proof material dried upon its surface.

20 For the manufacture of the various parts of a harness to which our invention is applicable, there are therefore needed suitable molds to compress and shape the article in the desired form, and each article requires to be wholly 25 finished in the desired form before the final coating of water-proof material is dried into and upon it.

When the article is to be protected by 30 japan, it is preferably dipped into the latter, and the heat subsequently applied tends to saturate the porous parts of the article with the japan, so that its substance remains water-proof when abraded or cut.

With the japan coating any suitable cement 35 may be used in uniting the scraps, and when pressed in molds and finished with a highly-polished coat of japan they are readily recognized as new articles of manufacture, from the unusual firmness and solidity of their texture 40 and great resistance to wear and moisture.

We are fully aware that it is not new to unite 45 scraps of leather by paste or cement, and that such materials have been formed into flat sheets and worked up into insoles for shoes.

45 We are also aware that a patent was issued to O. Nichols on December 14, 1875, for the combination of leather scraps and alkaline

rosin paste "compressed into a uniform layer," and do not therefore make any claim to artificial leather in sheets. Our invention, however, differs from others, first, in producing the desired article in the required shape without seams or joints by molding the scraps to the proper form; and, second, in coating the surface with water-proof material, so that 55 neither the scraps nor cement may be disintegrated by exposure to the air and moisture. These differences forming the essential part of our improvement, it is obviously immaterial how the article is pressed to its final form, 60 whether by dies, molds, or rollers, or how the water-proof material is applied and secured to the article. The baking referred to herein is not therefore an essential step in our process, although requisite if hard japans are used. 65

With india-rubber varnish and other volatile varnishes and paints, no baking in an oven would be required to dry the coating properly.

We therefore claim our invention as follows: 70

1. The process herein shown and described for manufacturing certain parts of harness from leather scraps, which consists, first, in pasting the scraps together with cement in a suitable mold; second, in pressing the same 75 in a finishing-mold; third, in freeing the pressed article from its moisture; and, fourth, in applying a water-proof coating to the surface and drying the same thereon, all substantially as and for the purpose set forth. 80

2. A horse-collar or other analogous articles of harness formed of scraps of leather, united by suitable cement and pressed to their finished form, and having a coating of water-proof material, substantially as herein set 85 forth.

In testimony whereof we have hereunto set our hands in the presence of two subscribing witnesses.

JAMES STANLEY.

THEODORE F. LEMASSENA.
